METHOD OF MAKING DIES OR PUNCHES

Joseph J. Tomalis, Providence, R. I., assignor to
 American Screw Company, Providence, R. I.,
 a corporation of Rhode Island

Application October 3, 1935, Serial No. 43,399

8 Claims. (Cl. 76—107)

This invention relates to punches and to the method of making the same, and more particularly to punches of the type used in forming recesses in the heads of screws.

It is a general object of the present invention to provide a novel and improved punch and method of making the same.

An important feature of the invention resides in the construction of a punch comprising a projection or nub extending integrally from a shoulder on the end of a metal bar, wherein the metal of the punch is compressed and upset as a result of cold pressing into a matrix and wherein simultaneously a fillet is formed at the junction of all of the surfaces of the projection and the said shoulder.

Another important feature of the invention resides in the method of forming a punch by first roughing it out by conventional tool-room methods using rotating tools and then forcing the punch projection cold into a matrix which changes the heretofore machined surfaces and the shape of the projection, compresses the metal and forms a fillet of short radius at the junction of the machined surfaces and the shoulder on the bar from which the punch projection is formed.

A further important feature of the invention resides in the forming of the punch proper first with arcuate surfaces and then reducing these surfaces to true planes in a cold forming operation using a matrix.

Other and further features and objects of the invention will be more apparent to those skilled in the art upon a consideration of the accompanying drawing and following specification, wherein is disclosed a single exemplary embodiment of both the article and method, with the understanding however, that such changes and deviations may be made therein as fall within the scope of the appended claims without departing from the spirit of the invention.

In said drawing:

Figure 1 represents a bar or rod of metal prior to the operations forming the punch;

Figure 2 shows the same rod after turning in a lathe to form the punch nub thereon;

Figure 3 illustrates the operation of end milling the grooves;

Figure 4 is an end view of the incompletely formed punch resulting from the operation of Figure 3;

Figure 5 and the following figures are all on an enlarged scale and Figure 5 shows the incompletely formed punch about to be driven into the

matrix which is illustrated in vertical central section;

Figure 6 is a plan view of the matrix;

Figure 7 is a side elevation of the completed punch; and

Figure 8 is an end view thereof.

It has long been proposed to form screws with some form of screw driver receiving recesses other than the conventional transverse kerf. From among these suggestions a recess of cruciform cross-section has been successfully adapted and commercialized. It is substantially shown in the patent to Pearson, No. 308,246, granted November 18, 1884 for Screw, although substantial improvements have subsequently been made.

The form of recess now manufactured in such screws may be considered substantially like that shown in the matrix of Figure 6 and comprises four symmetrically disposed wing slots radiating from a central opening. The wing slots taper in length from a maximum at the head of the screw to substantially the size of the opening at the bottom of the recess but remain substantially uniform in width at their edges, thickening however on merging with the center. The walls of the wing slots and the walls of the connecting surface comprise a series of flat or plane surfaces, rather than arcuate ones, and it has been demonstrated that these are highly desirable and in fact essential in holding the screw driver in the slot when considerable resistance to the entrance of the screw is exerted.

Recesses of the type just described are formed in the crudely up-set screw heads at a certain stage in their process of manufacture by holding the screw in a suitable anvil and forcing a properly shaped punch to the desired depth into the metal of the head while it is cold. This operation is an extremely severe one both on the metal of the screw and on the metal of the punch. The punch must be formed to the reverse of the recess in the screw, and because of the severeness of the operation and the small size the punches are consumed rapidly. They must be exact in size and shape so that the fit of the recess on the screw driver is such that the screw can be held in place on the end of the driver for insertion into difficult places. This means that no substantial variation in the size of the recess, and hence the punch, is permitted.

With the rapid wear on the punches, some method is required for making them easily, cheaply and rapidly. Unfortunately, the usual tool-room methods are not applicable to finish the punch because of the plane surfaces heretofore

referred to existing within the concavities between the wings and because these surfaces have a general splay or flare from tip to base of the punch.

5 In accordance with the present invention, these conventional tool-room practices are first used to form a developed punch shape which is subsequently and by an additional operation changed to the exact desired final form while also being 10 improved in strength and texture of the metal.

A suitable metal stock is used from which to form the punches, preferably tool steel cut into short lengths of rod 10 such as shown in Figure 1. It is preferably circular and of a convenient 15 diameter to be held in the punching machine head. By turning in a lathe there is provided a substantially flat shoulder 11 having projecting from the center thereof a tapered nub 12, the outline of which can be considered as formed to 20 the shape resulting from rotating a wing of a completed punch about the axis of the punch. In other words, it is a figure of rotation which can be formed on a lathe.

To provide the alternate wings and grooves, 25 four of each, an end mill 14 of conventional construction is mounted in a milling machine and the rod 10 supported in the vise thereof so that the tool is presented along an axis at a slight angle to the vertical axis of the rod and the nub. 30 The axis of the tool lies between the axis of the rod and the inclined surface of the nub. With the proper displacement from the center of the nub, this end mill is moved axially to cut each inclined groove 15 substantially to the depth of 35 the shoulder 11. The rod is indexed through 90° for each succeeding cut until there is formed the semi-finished punch shown in Figures 3 and 4, all surfaces of which are curved and those of the groove 15 being arcuate. The surfaces 40 of the wings are arcuate in horizontal section and curved in vertical section in accordance with the predetermined shape of the wings. Because of the angle at which the milling cutter is advanced, the edges of the wings of the incomplete punch 45 increase in width from tip to base as seen in Figures 3, 4 and 5, although this is not desired in the finished punch.

To produce the final shape of the punch, it is forced by hydraulic pressure or otherwise driven 50 into a matrix, the recess in which is the exact counter-part of that desired in the screws. Referring to Figures 5 and 6, it will be seen that the matrix is formed in a block 20 of suitable metal which is hollowed out to provide the wing 55 recesses 21, having the flat surfaces 22 tapering as shown at 23 and the intermediate flat surfaces 24 and 25 also tapering as shown. Axially of the matrix is an opening 26 to permit tip clearance and for the passage of a knock-out bar if required. 60 The amount of metal in the crudely finished nub of the punch is slightly greater than would be normally accepted in the recess of the matrix causing a small amount of compression and upset of the metal as well as a change of its shape 65 as the punch is forced into the matrix. Any accidental considerable excess of the metal will be forced down into the opening 26. The crude nub is thus formed to exactly the size and shape desired and the working and compressing of the metal thereof strengthens, densifies and hardens it, although as a final operation before use the punch is hardened by a suitable heat treatment.

It has been found highly desirable for various reasons that the junction of the surfaces of the recess in a screw head with the outer surface of

the head be on a radius of small curvature and since it is difficult to form such a radius after the recess is punched and the screw head shaved, the fillet-like radii are put on the punch at the junction of each of its surfaces with the flat 5 shoulder 11. Such a radius can be seen crudely at 28 in Figure 2 where it will be effective only on the bases of the outer faces of the wings. In Figures 3, 4, and 5 will be seen that the junctions 10 of the concave or arcuate grooves with the shoulder are almost sharp, although a slight radius can be given by properly shaping the milling cutter. The final radius, however, at all these junctions is formed by the matrix which has a suitable rounding off of all of the junctions where 15 any surface of the recess intersects the top surface of the block 20, as can be seen at 29.

The matrix recess is formed by the usual die sinking methods which are of course more expensive than tool-room practice, but the matrix 20 is not exceedingly difficult to form since the flat surfaces therein are on generally convex rather than concave surfaces as in the punch.

The curvature of the junction of the surfaces of the punch and its shoulder may be likened to 25 fillets strengthening the punch at the point of application of the stresses thereon where they are transferred to the larger section of the rod. Thus they have the added function of strengthening the punch as well as producing in the screw 30 a great improvement in appearance, function and ease of manufacture.

Although the operation of forming the punch by driving it into a matrix has been described as a cold typing operation, it nevertheless may be 35 desirable for larger sizes of punches to first heat the crudely formed punch to assist in its shaping in the matrix, thereby lessening the wear on the matrix and greatly increasing its life. Since a final hardening by heat treatment is necessary 40 for the punch anyhow, this heating does no harm although it does introduce difficulty in the way of scale which might change the very close dimensions of the punch surfaces.

Having thus described the invention, what is 45 claimed as new and desired to be secured by Letters Patent is:

1. The method of forming a punch for making screw head recesses of cruciform plan comprising turning the end of a bar of steel to provide a flat 50 shoulder and a projecting nub, grooving the nub substantially longitudinally with an end mill to form alternate wings and grooves and then compressing and upsetting the nub in a matrix to change the shapes of the surfaces formed by the 55 milling operations.

2. The method of forming a punch for making screw head recesses of cruciform plan comprising turning the end of a bar of steel to provide a flat 60 shoulder and a projecting nub, grooving the sides 65 of the nub with an end mill having its axis nearly parallel to the axis of the nub to form thereon alternate grooves and wings and then compressing and upsetting the nub in a matrix to change by pressure only at least the shapes of the arcuate surfaces formed by the milling operations.

3. The method of forming a punch for making screw head recesses of cruciform plan comprising turning the end of a bar of metal to provide a flat shoulder with a nub projecting therefrom 70 having in longitudinal section substantially the form of a similar section through the wings of a finished punch, grooving the sides of the nub substantially longitudinally with a rotary tool to form alternate grooves, extending to said shoul- 75

der, and wings and then forcing the nub into a matrix to change by pressure only the shapes of all arcuate surfaces formed by the rotary tool.

4. The method of forming a punch for making screw head recesses of cruciform plan comprising turning the end of a bar of metal to provide a flat shoulder with a tapering nub projecting therefrom having in longitudinal section substantially the form of a similar section through the wings of a finished punch, grooving the sides of the nub substantially longitudinally with a rotary tool having an axis nearly parallel to the axis of the nub to form alternate grooves, extending to said shoulder, and wings and then forcing the nub into a matrix to change by pressure only the shapes of all arcuate surfaces formed by the rotary tool to surfaces flat transversely of the nub.

5. The method of forming a punch for making screw head recesses of cruciform plan comprising turning the end of a bar of metal to provide a flat shoulder with a nub projecting therefrom having in longitudinal section substantially the form of a similar section through the wings of a finished punch, grooving the sides of the nub substantially longitudinally with a rotary tool to form alternate grooves, extending to said shoulder, and wings, reshaping said grooves and wings and forming a rounded fillet at the junction of each nub surface with the said shoulder solely by pressure on said surfaces.

6. The method of forming a punch for making screw head recesses of cruciform plan comprising turning the end of a bar of tool steel to provide a shoulder and a tapering nub projecting therefrom, grooving the sides of the nub at a

slight inclination to the nub axis with an end mill to form alternate grooves and wings each extending to the shoulder, forcing the nub cold into a matrix to change the shape of all surfaces formed by the mill and to compress the metal of the nub and thereafter hardening the nub.

7. The method of forming a punch for making screw head recesses of cruciform plan comprising turning the end of a bar of steel to provide a substantially flat shoulder with a tapering nub projecting therefrom, grooving the nub with an end mill rotating on an axis extending between the nub axis and nub surface to thus form alternate grooves and wings each extending to the shoulder, forcing the nub into a matrix to change all arcuate surfaces formed by the mill to flat surfaces and simultaneously forming a rounded fillet at the junction of each changed surface and the said shoulder.

8. The method of forming a punch for making screw head recesses of cruciform plan comprising turning the end of a bar of steel to provide a substantially flat shoulder with a tapering nub projecting therefrom, grooving the nub with an end mill rotating on an axis extending between the nub axis and nub surface to thus form alternate grooves and wings each extending to the shoulder, said wings because of said angled mill axis being broader at the base than tip, forcing the nub into a matrix to change all arcuate surfaces formed by the mill to flat surfaces and reducing the wings to uniform edge thickness and simultaneously forming a rounded fillet at the junction of each changed surface and the said shoulder.
